UNITED STATES PATENT OFFICE.

AUGUST D. COOK, OF LAWRENCEBURG, INDIANA.

STRAINER FOR DRIVEN WELLS.

1,079,216.

Specification of Letters Patent.

Patented Nov. 18, 1913.

Application filed March 6, 1911. Serial No. 612,560.

To all whom it may concern:

Be it known that I, AUGUST D. COOK, a citizen of the United States, residing at Lawrenceburg, in the county of Dearborn and 5 State of Indiana, have invented certain new and useful Improvements in Strainers for Driven Wells, of which the following is a specification.

My said invention consists in an improved 10 form of strainers for the lower end of driven well tubes, whereby such a strainer is provided which is not only very efficient in use, but one which will not be liable to be injured or destroyed in the process of driving, or be 15 come filled up or clogged with the dirt, or other material, and thus rendered inefficient, all as will be hereinafter more fully described and claimed.

Referring to the accompanying drawings, 20 which are made a part hereof and on which similar reference characters indicate similar parts, Figure 1 is a side elevation of the lower end of a well tube provided with the strainer of my improved form, Fig. 2 a central vertical section of the same indicating the tube as in the bottom of a well, Fig. 3 a view similar to Fig. 1 showing a modified form, Fig. 4 a view showing said modified form as in use in the well, and Figs. 5, 6 and 30 7 detail views illustrating the form of parts on an enlarged scale.

In said drawings the portions marked A represent the well tube, B the lower perforated section thereof, and C my improved 35 strainer. The well tube A and the perforated section B on the lower end thereof are of common form and require no special description. The strainer C is preferably composed of short sections of brass tubing 40 formed with a series of equi-distant parallel slots and a series of internal circumferential ribs c. Said internal ribs are formed by milling out the metal on the interior of the tube section between the ribs, by casting, or 45 in any other approved manner.

A drive point B' is mounted, by means of a screw-threaded engagement, on the lower end of perforated section B and the sections of strainer C are slipped over said 50 section B, the internal ribs c preferably fitting snugly around the circumference of said section, leaving a free space between the strainer C and section B equal to the thickness of said ribs. The sections of strainer 55 C are clamped longitudinally between the drive point B' and a screw-threaded ring

A', which serves as a connection between section B and tube A, being screwed onto the upper end of said section B and having the lower end of tube A screwed into it, thus connecting the several parts, as best shown in Fig. 2. The sections composing the strainer C are each slotted longitudinally, the slots extending to a depth to form openings between the ribs c, but not of a sufficient depth to cut said ribs and thus weaken the structure. Said slots may be formed with parallel sides as shown in Fig. 6 or may have their sides tapered to extend at a slight angle away from each other from the outside toward the inside, as shown in Fig. 7, and thus provide for the freeing of said slots from dirt more readily.

In the structure shown in Figs. 3 and 4 the tube A is first driven to the depth desired and then a strainer composed of the sections C² and C³, or as many sections as may be required, is dropped into the bottom of the well when tube A is lifted for the distance necessary and serves as the lower section of the well tube as well as the strainer. The lower section of such a strainer is also preferably filled with a screw-threaded block c², as shown. In such a structure the strainer is made to slide snugly down the well tube and any length desired may be provided by screwing the required number of sections together, as indicated in Fig. 3. In such a structure, also, each section is formed solid at each end in order to afford the necessary thickness to form the inter-engaging screw-threaded ends and preserve a smooth exterior to the strainer as a whole. A lead packing ring C³ is also preferably mounted on the top of the top section and within the lower end of tube and a conical swage block forced into the top thereof to spread the same outwardly and form a tight joint to prevent sand and dirt from being sucked into the tube through said joint.

It will be understood that, while I have shown the slots in the strainer as running vertically and the internal ribs circumferentially and regard this form as preferable, inasmuch as it offers no sharp edges to resist the work of driving, yet the slots may be formed to extend in any desired direction and the ribs to extend substantially across the slots, in order to form a rigid unitary structure. Whichever form may be used it will be seen that each section of the strainer is a single piece of metal, the exterior being

2
composed of narrow strips with slots between them held together by integral ribs formed by milling, or otherwise, to cut out portions of the interior of the original tubular sections, as before described.

5 Having thus fully described my said invention, what I claim as new and desire to secure by Letters Patent, is:

- 10 1. A strainer for driven wells comprising tubular sections fitted and secured together each made of a single piece of metal having a uniform smooth exterior, the solid end of one section against the solid end of the adjacent section, each section being correspondingly slotted through the body thereof and formed with internal integral ribs extending across said slots, substantially as set forth.
- 15

2. A driven well structure comprising a well tube, a lower perforated section secured thereto, a drive point on the lower end of said perforated section, a strainer surrounding said perforated section comprising single piece tubular sections formed with straining slots and with integral internal ribs crossing said slots, said internal ribs resting against the outer wall of said perforated section, substantially as set forth.

In witness whereof, I, have hereunto set my hand and seal at Lawrenceburg, Indiana, this fourth day of March, A. D. nineteen hundred and eleven.

AUGUST D. COOK. [L. S.]
